Application May 9, 1945, Serial No. 592,808

12 Claims. (Cl. 89—6.5)

(Granted under Title 35, U. S. Code (1952),
sec. 266)

1

This invention relates to major caliber guns employing semi-fixed ammunition and intended to be effective for both anti-aircraft and surface fire, and more especially to improvements in fuze setting mechanism for use with such guns.

In an application filed November 28, 1942, Serial No. 467,182 of George A. Chadwick, et al., there is described and illustrated, a gun of the type with which our invention is intended to be used. One feature of the invention described therein resides in a combination of elements which includes a tray fastened to the slide of the gun adapted to receive ammunition, a stop arranged to engage the ammunition and a fuze setting mechanism adapted to be moved longitudinally of the tray to engage the ammunition at the forward or loading end of the tray to set the fuze and thereafter to move the ammunition from the forward position rearwardly to a position in which it is subsequently moved transversely of the gun to a ramming position. The fuze setting mechanism included a socket, for the reception of the nose of the ammunition, a portion of which is movable with respect to another portion and associated with the socket are means adapted to engage lugs on the nose and the fuze ring, respectively. One of the aforesaid means is fixed and the other is movable with the movable portion of the socket to engage the lug on the nose and to rotate it with respect to the fuze ring, thereby to set it at any desired predetermined position. As thus described and in previous similar devices, the ammunition must be loaded into the tray with sufficient care to assure engagement of the fixed means with the lug on the nose of the ammunition.

It is an object of this invention to provide an improved fuze setting mechanism which will be operative irrespective of how the ammunition is placed in the tray, which will be rugged and which may be installed in the gun assembly referred to above with a minimum of modification.

As illustrated herein, one feature of the invention resides in a mechanism for rotating the nose of the ammunition with respect to the fuze ring, thereby to establish a given fuze setting including relatively movable elements adapted to engage respectively, slots in the nose and the fuze ring, and means for effecting relative movement between the elements to produce an ultimate predetermined angular distance between the elements thereby to produce an ultimate predetermined angular distance between the slots with

2

respect to the elements. More specifically, there are annular concentrically disposed members adapted to receive the nose of the ammunition and with which there are associated latches adapted to engage these slots in the nose and the fuze ring of the ammunition, the latches being movable in opposite directions, relative to each other. The latches are normally spring pressed inwardly of the inner surface of the annular members, but are capable of being moved to a position flush with the surface of the annular members, by the entrance of the nose of the ammunition into the annular members. When rotation of the annular members takes place, and the latches are brought opposite the aforesaid slots, they automatically snap into the slots. The one of the latches which drops into the slot in the fuze ring will immediately cease rotation because of the weight of the ammunition which resists rotation, whereupon the other latch, which engages the nose, moves twice as fast due to differential gearing employed for rotation of the members. This latter latch is constructed upon resistance to rotation, for instance, due to failure of the nose to turn, to be disengaged from the slot in the nose, thereby to prevent damage to the mechanism. The latches are mounted on the annular members which are rotated relative to each other by the aforesaid differential gearing, the latter being adapted to be driven by pins which engage a pair of grooves formed in a shaft. The grooves comprise a helical portion and a straight portion, the straight portion being located at the rear end of the shaft. The aforesaid annular members and associated latches constitute the fuze setter and rotation of the aforesaid pins to engage the latches with the slots and set the fuze is accomplished by a combination of movement of the fuze setter longitudinally of the shaft and rotation of the shaft. The movement of the fuze setter, and hence, the pins along the helical portions of the grooves in the shaft effects engagement of the latches with the slots in the nose and fuze ring and to insure such engagement, the length of the helical portions of the grooves is designed so that movement of the pins from one end to the other by movement of the fuze setter along the shaft will cause the latches to be moved through at least 360° of rotation in opposite directions after engagement with the slots in the nose and fuze ring. The fuze setting is accomplished by rotation of the shaft in response to orders fed in from an indicator regulator coincidently with the rearward movement of the

fuze setter which rotates the pins to cause a displacement of the latches by an amount corresponding to the desired fuze setting. Continued movement of the fuze setter beyond the helical portions of the grooves moves the pins from the helical portions of the grooves to the straight portions thereof, whereupon final fuze setting, if it differs from that already fed in, takes place by further rotation of the shaft. A chain is provided for moving the fuze setter from its loading position to its firing position along the shaft and the shaft is operably connected to an indicator regulator and is rotated thereby in response to orders set into the indicator regulator in the usual manner.

The details of the aforesaid construction will now be described with reference to the accompanying drawings, in which:

Fig. 1 is a perspective view of our improved fuze setting mechanism partly in section;

Fig. 2 is a vertical section through the fuze setting mechanism on the line 2—2 of Fig. 4;

Fig. 2a is a fragmentary section of the fuze setter drive shaft showing the straight portion of the rear end thereof;

Fig. 12 is a perspective view of the gun showing the fuze setting apparatus attached to the ammunition tray of a gun assembly of the type 40 with which it is used; and

Fig. 13 is a side view partly in section showing the fuze setting mechanism at the forward end of the gun.

The fuze setting mechanism of the present invention is used in conjunction with the dual purpose gun, a perspective view of which is shown in Fig. 12, which forms the subject matter of an application filed in the name of George A. Chadwick, et al., Serial No. 467,182, filed November 28, 1942.

As shown herein, referring specifically to Fig. 12, the fuze setting mechanism 10 is mounted for movement longitudinally of a tray 12 which is fastened to the gun slide 14 in such a position that it tilts with the slide 14 about the gun trunnion, not shown. The longitudinal center line of the tray 12 lies in a vertical plane parallel to the bore of the gun. As will be seen by reference to Fig. 12, the ammunition consists of a projectile 20 and a powder case 22 which are placed in the tray with the base 24 of the projectile against the mouth of the powder case. A stop 26 which is normally locked in a forward position engages the base of the powder case and prevents it from sliding rearwardly when the gun is elevated. The stop is adapted to be moved rearwardly with the ammunition as the latter is moved rearwardly in the tray to the dotted line position, shown in Fig. 12, from which position the ammunition is then moved transversely of the gun to a position behind the breech from which it may be rammed into the breech of the gun. The projectile 20 is supported in the tray 12 on a slide 32, Figs. 4 and 13, and the latter

5 and the fuze setting mechanism which is fastened thereto as will appear hereinafter, are moved rearwardly of the tray 12 by a sprocket and chain 44 and 46.

Referring to Fig. 1, there is shown in somewhat more detail, the projectile 20. The projectile 20 comprises a body 36, and a time fuze consisting of a fuze ring 38 and nose 40, the fuze ring having formed therein a slot 42 and the nose having formed therein a slot 244. A scale 246, graduated in seconds of time is formed on the fuze ring and by rotation of the nose with respect to the fuze ring, the fuze may be set to cause the projectile to explode at the end of any given length of time.

The rotation of the nose 40 to accomplish setting the fuze to go off at a predetermined time is accomplished herein by the fuze setting mechanism 10 which is shown in detail in Figs. 1 and 2. The fuze setting mechanism as shown in Figs. 1 and 2 comprises a housing 48 which is fastened to the projectile slide 32, by a strap 50 and cap 51. The slide 32 is mounted for sliding movement along the tray 12. Flanges 53 and 55 are formed on the strap and cap and through these flanges are passed bolts 57 by which the cap may be fastened to the strap to clamp the housing to the slide, Fig. 5. As illustrated, the tray 12 is provided with oppositely disposed parallel grooves 13, Fig. 4, adapted slidably to receive oppositely disposed tongues 33 formed on the slide 32.

The housing 48 is substantially cylindrical and has a cylindrical chamber 54, Fig. 2, therein, adapted to receive a pair of substantially conical members 56 and 58 for rotation therein, the members 56 and 58 being concentrically arranged and adapted to rotate about a common axis. The conical member 56 is supported for rotation in the housing 48 by a ball bearing assembly 60. The forward end of the conical member 56 has formed integral therewith, a bevel gear 62 which, as will appear hereinafter, meshes with other gearing to be described, for rotating the member 56. The rear end of the member 56 has fastened thereto, an annular ring 64, the ring being secured to the member 56 by bolts 65 which are passed through an annular flange 67 formed integral with the outer surface of the member 56. In the annular ring 64 there is formed an opening 66, Figs. 2 and 10, through which there projects a latch 68 pivotally supported on the ring 64 at 70 and yieldably pressed inwardly of the inner surface of the member 58 by a spring 72. The member 58 is rotatably supported within the member 56 by ball bearing assemblies 74 and 76, the former being seated in an annular recess 78 formed on the inner surface of the member 56 and the latter being seated in an opening 80 formed in the forward end of the member 56. The forward end of the member 58 is closed and prolonged to form a shaft 82 to which is fastened a gear 84 adapted to rotate the shaft 82 and hence the member 58. The rear end of the member 58 has an annular rim 85 formed thereon and an oversize opening 86 is provided in the flange, Fig. 11, through which the tip of a latch 88 projects, the latch being pivotally supported at 90 in elongated holes or slots 90a on the rim 85 of the member 58 and yieldably pressed inwardly of the inner surface of the member 58 by a spring 92. An annular recess 94 is formed in the annular rim 85 and in the recess there is seated a U-shaped resilient member 96, Figs. 9 and 11, the opposite ends of which are adapted to engage a notch 98 formed

in the member 58 and a notch 100 formed in the base of the latch 88. Thus it will be seen that spring member 96 urges the support pin 90 of latch 88 to the inner end of slot 90a while spring 92 urges the fuze engaging tip of latch 88 inwardly. On the latch 88 there is formed a cam 185 which cooperates with a cam surface 186 formed at one side of the slot 86, hence if for any reason the nose jams and will not turn, the resistance to rotation in a clockwise direction as viewed in Fig. 11 will cause the latch, which is pivoted at 90 to slide in elongated holes or slots 90a to the left as viewed in Fig. 11 against the resistance of the U-shaped spring 96 so as to bring the cam 185 and cam surface 186 together to lift the latch 88 out of the slot 86, thus disengaging it and preventing damage to the mechanism.

The rotation of the aforesaid members 56 and 58 is accomplished by a train of gears. As illustrated, gears 102, 104 and 106 are provided, the gears 102 and 106 meshing with the gear 62 at the base of the member 55 and being mounted for free rotation on a pair of studs 108 and 112, the latter being screwed into the hub 110 of a disc 111, Fig. 7, which is mounted for free rotation on the shaft 82. The disc 111 has a rim 113 and diametrically opposed openings 115 adapted to receive the gears 102 and 106. The gear 104 is double faced and the gears 102 and 106 mesh with one face thereof, the gear 104 being mounted for free rotation on the shaft 82. Fastened to the rim 113 by bolts 117 is a ring gear 119 which meshes with a gear 116, the latter being journaled in ball bearing assemblies 118 and 120. The ball bearing assembly 118 is seated in a recess 122 formed in the housing 48 and the assembly 120 is seated in a recess 124 formed in a cap 126. The cap 126 is fastened to the rear end of the housing 48 by bolts 128 and has an aperture 130 formed therein in which there is seated a ball bearing assembly 132 adapted to receive the forward end of the shaft 82 which is reduced at 134 to pass through the bearing assembly. A plate 136 is fastened by bolts 138 over the end of the aperture 130 to enclose the end of the shaft 82 and retain bearing assembly 132. An aperture 140 is formed in the cap 126 in which there is mounted a sleeve 141 in which there are disposed ball bearing assemblies 142 adapted to rotatably receive a stub shaft 144 to one end of which there is attached a gear 146. The stub shaft is supported in position by a nut 143 threaded on the end of the stub shaft and resting on the upper one of the ball bearing assemblies. A cover plate 145 is arranged to close the opening. The gear 146 meshes with the gear 84 and with the opposite face of the gear 104, and hence, provides means for rotating the gear 84, the shaft 82 and the member 58. The reason for the rotating gear 146 is to insure that the members 56 and 58 carrying the latches 68 and 88 have a determinable angular displacement for a given angular displacement of ring gear 119. From Fig. 2, it can be seen that members 56 and 58 cannot rotate in the same direction but will always rotate in opposite directions for a given direction of rotation of the ring gear 119. Moreover, the gear train is so designed that the angular displacement of latches 68 and 88 is always a constant ratio to the angular displacement of the ring gear 119. That is, if one of the members 68 or 88 is restrained from movement, the other member 68 or 88 will rotate at twice the speed it would be moving if both members 68 and 88

were moving. This is also true of any intermediate speed of either member from a maximum speed to a minimum speed. The gear 116 is rotated to drive the differential gearing just described, by a gear 148, the latter being formed on a sleeve 150 which is journaled in a bearing sleeve 152 supported in the cap 126. Rotation of the sleeve 150 is provided for by a pair of diametrically disposed pins 156 fixed in the walls of the sleeve and extending inwardly thereof to the inner ends of which are fastened blocks 158. The blocks are adapted to slide in a pair of grooves 160 formed in a shaft 162 which is parallel to the tray 12. The grooves consist of helical portions which extend from the forward end of the shaft rearwardly. Near the rear end of the shaft the helical grooves terminate in straight portions 160a parallel with the axis of the shaft. It is evident that by rotation of the shaft 162 or relative movement of the fuze setting mechanism longitudinally of the shaft 162 or by a combination of these, the sleeve 150 may be caused to rotate, and hence, to produce rotation of the differential gearing in a manner to rotate the members 56 and 58. It is to be observed, however, that when the fuze setter approaches its rearward position, the blocks 158 move into the straight portions of the grooves 160 and from that point, relative movement of the latches will take place only by rotation of the shaft 162. The shaft 162 has a reduced end 164, Fig. 2, which is connected to an indicator regulator, IR, Fig. 12. Fuze setting orders are continually fed from the IR by way of a shaft 163 and gearing 165 to the shaft 162 in accordance with calculations made in the plotting room. It is evident, therefore, that the shaft 162 is continually rotating in one direction or the other which in turn rotates the members 56 and 58 with respect to each other to establish a predetermined distance between the latches 68 and 88 which corresponds to a given number of seconds of fuze time.

The rotation of the latches in opposite directions by reason of the movement of the fuze setter longitudinally of the shaft 162 from the forward or loading position aft toward the final fuze-setting position is for the purpose of insuring engagement of the latches with the notches in the nose and fuze ring, irrespective of their original position with respect to each other or their positions with respect to the latches. This is accomplished by designing the helical grooves so that the movement of the fuze setter from one end of the grooves to the other will rotate the latches in opposite directions through at least 720°, after they engage the slots in the nose and fuze ring. Hence, if at the moment the fuze setter contacts the nose of the projectile the latches are displaced a given amount, they will again be displaced by the same amount at the terminal end of the helical grooves. It is evident, therefore, that if the projectile is dropped into the tray and the projectile slide and fuze setter together move rearwardly along the shaft, the latches are bound to pick up the notches in the nose and fuze ring somewhere in their relative movement and bring them into a position corresponding to the initial displacement of the latches when the fuze setter reaches the ends of the helical grooves. As soon as the fuze setter reaches the straight portions of the grooves, any further rotation of the latches can only take place by rotation of the shaft 162. Since the fuze at this time is set for a time dictated by the initial displacement of the latches when the

fuze setter leaves the helical grooves, rotation of the shaft 162 when the fuze setter is moving along the straight portions of the grooves will rotate the nose with respect to the fuze ring to set the fuze in accordance with the orders fed into the shaft from the IR. The operation of the device has been described above on the assumption that the first part of the movement of the fuze setter, that is, from the forward ends of the helical grooves to the rear ends thereof, consists only of engaging the latches and bringing the nose and fuze ring into position corresponding to the initial displacement between the latches and that the final rearward movement along the straight portion of the shaft 162 is accomplished by the fuze setting. This would be true only if the IR fed in a constant fuze setting order for the entire time during which the fuze setter moved rearwardly. As a matter of fact, the shaft 162 is continually being rotated by the IR in response to changes in the fuze setting orders, and hence, the rotation of the shaft 162 is taking place during the entire time that the fuze setter is moving rearwardly from its loading position to its final fuze-setting position. Thus the engagement of the latches with the slots in the nose and fuze ring and the fuze setting take place simultaneously. The movement of the fuze setting mechanism bodily longitudinally of the shaft 162 is accomplished as follows: A boss 168 is formed on the fuze setter and has an opening 170 therein to which there is attached by means of a bolt, one end of the chain 46. Reciprocation of this chain 46 will move the fuze setting mechanism and projectile 35 slide longitudinally along the shaft 162 and it is to be observed that to permit such movement, a slot 171 is formed along the bottom of the tray 12, through which the projectile slide boss 168 passes, and an opening 171 is provided in the 40 boss through which the shaft 162 freely passes.

Heretofore, the fuze setting mechanism was described as being movable from a position forwardly of the tray 12, Fig. 12, to a final fuze-setting position at the rear thereof, in which position the ammunition was in a position to be moved transversely of the gun and to be rammed into the breech. Since this gun is a dual purpose gun, that is, suitable for both surface and anti-aircraft, the gun will be fired at high angles and in order to prevent the ammunition from sliding out of the tray at high angles of elevation, the stop 26, referred to above, was provided. The stop 26, together with the fuze setting mechanism, engage the opposite ends of the 50 ammunition 20 and hold it firmly in the tray. During the rearward movement of the ammunition, however, this stop must be yieldable and movable with the ammunition to the rearward position, hence, there is provided means for releasing the stop which is normally locked in a forward position and permitting its movement with the ammunition in response to the force applied by the rearward movement of the fuze setting mechanism. To this end, there is threaded into the rear end of the housing 43, an annular ring 172, Fig. 2, and in this ring there is slidably mounted for movement axially of the fuze setting mechanism, an annular ring 174. This latter annular ring 174 is yieldably held in the ring 172 against springs 176, by bolts 178 which are passed through ring 174 and are threaded into the ring 172. An annular ring of some resilient material 181 is disposed on the inner

5 surface of the annular ring 174 to guide the nose of the ammunition as it moves into the fuze setting mechanism and to prevent binding, this ring is held in place by a cap ring 182 which is bolted together with the ring 174 to the ring 172. As the fuze setting mechanism moves rearwardly and engages the nose of the ammunition, and as the ammunition moves into the fuze setting mechanism, the body portion thereof engages the ring 181 and as the pressure increases, the ring 174 is forced inwardly against the spring 176. A pair of levers 179, Fig. 4, are pivotally mounted at 180 on opposite sides of the casing 43. Each lever has a flat surface 183, Fig. 3, near its free end adapted to bear against a flat surface 184 formed on the inner side of a radial extension on the ring 192, Fig. 4. In the flange 53 formed at the ends of the cap 51, are provided bosses through which are formed slideways 186 adapted to receive rods 188. One end of each rod bears against the free end of a lever 179 and the other is necked down at 190 to receive a spring 192. One end of each spring 192 is seated in a recess 194 formed in the casing and the other is telescoped over the end of the neck 190 so that the springs serve to urge the rods 188 toward the right, as seen in Fig. 3, thereby to push the levers 179 in a clockwise direction about their pivots. Enlargements 196 are formed integral with the rods and one end of each enlargement serves as a shoulder against which the springs 192 bear. A recess 198 is formed in each enlargement and is adapted to receive the ball end 200 at the end of an arm 202. The arms 202 are secured by nuts 204, which are screwed onto the opposite end of a shaft 204a and which is revolvable in a boss 206 formed on the housing 43. One of the arms 202 has formed integral therewith an arm 208 substantially at right angles thereto and the end of this arm is adapted to initiate the operation of hydraulic means, not shown herein, thereby to release the stop 26 and allow it to move rearwardly with the ammunition as the fuze setting mechanism moves rearwardly to push the ammunition into the position in which it is ready for transverse movement.

The operation of the fuze setting mechanism will now be described with reference to the loading of the gun. Initially the fuze setting mechanism 10 is at the forward or loading end of the tray 12 and is moved aft into its final fuze-setting position by the sprocket and chain 44 and 45 in such timed relation with reference to the firing of the gun that ammunition is always ready to be rammed for the firing of the gun. Continuous orders for the fuze setting mechanism are transmitted from the control room through the indicator regulator IR by way of the shaft 163 to the shaft 162 through the gearing 165 to actuate the fuze setting mechanism so that the latches 68 and 88 are moved relative to each other to maintain the latest fuze setting. The loader places the powder case 22 on the tray 12 against the stop 26 and then places the projectile 20 on the tray 12 against the powder case, adjacent to the fuze setting mechanism. The tray operating lever, not shown, is then manipulated to cause rearward movement 60 of the fuze setter and as the fuze setting mechanism 10 begins to move rearwardly, since the ammunition is held stationary by the stop 26, the projectile slide 32 slides under the projectile until the fuze setting mechanism moves over 65 the nose 40 of the projectile, whereupon the

ring 181 is engaged by the nose and the ring 174 is pressed inwardly. This actuates the hydraulic means (not shown) which in turn releases the stop 26 and the fuze setting mechanism, ammunition and stop move rearwardly. As the nose enters the fuze setter, the latches 68 and 88 are pressed outwardly until they are flush with the inner surface of the members 56 and 58. As the fuze setter moves rearwardly the members 56 and 58 rotate relative to each other until one or the other of them falls into its slot. As soon as one of the latches falls into its slot, which will occur within two complete relative revolutions of the latches, it will be held stationary and the other will rotate 15 until it engages the slot, then the latches will relatively rotate to complete the desired angular displacement. During this rotation, the fuze setting orders are fed in continually and added or subtracted by the rotations of the shaft 162.

It is to be observed that if for any reason, such as dirt, corrosion, etc., the nose 40 becomes frozen with respect to the fuze ring and will not rotate, the latch 88 will automatically be thrown out of the recess 44 by the cam 185 which is formed integral with the latch adjacent to the inwardly projecting portion thereof, the cam being adapted to ride upwardly on the cam surface 186 which is formed in the opening 86 of the member 58 under the influence of lateral movement of the latch 88. This latch 88, as previously described, is held inwardly not only by the spring 92, but by a yieldable U-shaped member 96 which prevents disengagement of the latch 88 except under some unusual force such as would be offered by the resistance to rotation of the nose 40 when it becomes jammed or frozen in place.

The invention described herein may be manufactured and used by or for the Government of the United States of America for governmental purposes without the payment of any royalties thereon or therefor.

What is claimed is:

1. Fuze setting mechanism for a projectile having a nose fuze adapted to be preset by rotation of the nose with respect to the fuze ring, said nose and fuze ring having latch receiving slots, comprising two relatively rotatable annular members adapted to receive said nose, two latches pivotally mounted each on a different one of said members, yieldable means normally holding said latches inwardly of the inner surfaces of said annular members, said latches being adapted to be moved outwardly to a position flush with the inner surface of the annular members by insertion of said nose into said annular members, and to snap inwardly into the slots in the nose and fuze ring upon rotation of the members to bring the latches opposite said slots, means for relatively moving said members, a cam on a given one of said relatively rotatable members, the latch of said given member being shiftable on its pivotal mounting into and out of engagement with said cam, a spring urging said latch out of engagement with said cam, said given member being rotatable in a direction relative to the nose during the fuze setting operation whereby said cam is carried into lifting engagement with said latch against the resistance of said spring so as to disengage said latch from said nose.

2. Fuze setting mechanism for a projectile having a nose fuze adapted to be preset by rotation

5 of the nose with respect to the fuze ring, comprising a member having a recess therein adapted to receive the nose of the projectile, relatively movable latches associated with said member adapted to engage respectively slots in the nose and fuze ring when said nose is seated in the recess, a shaft, means for moving the said member along said shaft, and means operable by the movement of the member along the shaft and by rotation of the shaft to move the latches relative to each other to establish an angular distance between the slots a predetermined amount irrespective of the original position of the slots with respect to the latches.

3. Fuze setting mechanism for a projectile having a nose fuze adapted to be preset by rotation of the nose with respect to the fuze ring, comprising a member having a recess therein adapted to receive the nose of the projectile, relatively movable latches associated with said member adapted to engage respectively slots in said nose and fuze ring when said nose is seated in the recess, and means for effecting rotation of said latches comprising a pin, a shaft having a groove therein with which said pin cooperates, means for effecting movement between the shaft and said member to cause the latches to engage the notches, and means for rotating the shaft to establish a predetermined distance between said latches.

4. Fuze setting mechanism for a projectile having a nose fuze adapted to be preset by rotation of the nose with respect to the fuze ring, comprising a body, relatively movable elements mounted on said body adapted to engage respectively slots in said nose and fuze ring, a shaft, a groove in the shaft consisting of a helical portion and a straight portion, means associated with the body adapted to engage said groove, 40 said means being adapted by movement along the shaft to cause rotation of said movable elements and by rotation of the shaft to cause further rotation of said movable elements, means for moving the body along the shaft, and means for simultaneously rotating the shaft.

5. In a gun assembly, a barrel having a breech, an elongated tray supported adjacent said breech for receiving a round of ammunition having a nose fuze adapted to be preset by rotation of the nose with respect to the fuze ring, a fuze setting mechanism mounted for forward and rearward reciprocating movement along said tray and during its rearward movement being engageable with the nose of the ammunition, means 50 for moving the fuze setting mechanism forwardly and rearwardly of said tray and adapted during rearward movement of said fuze setting mechanism to carry the ammunition to a rearward position for loading into the gun breech, relatively movable elements associated with the fuze setting mechanism, said elements being adapted to engage the nose and fuze ring respectively, and a shaft supported adjacent said breech against axial movement operably associated with said movable elements, the said shaft containing a groove therein having a helical portion, drive means engaging said groove and adapted by the relative movement of the fuze setting mechanism lengthwise of the shaft to effect movement of the relatively moveable elements associated with the fuze setting mechanism whereby movement of the fuze setting mechanism longitudinally of the tray causes setting of the projectile fuze.

6. In a gun assembly, a barrel having a breech,

an elongated tray supported adjacent said breech for receiving a round of ammunition having a nose fuze adapted to be preset by rotation of the nose with respect to the fuze ring, fuze setting mechanism mounted for forward and rearward reciprocating movement along said tray and during its rearward movement being engageable with the nose of the ammunition, means for moving the fuze setting mechanism forwardly and rearwardly of said tray and adapted during rearward movement of said fuze setting mechanism to carry the ammunition to a rearward position for loading into the gun breech, relatively movable elements associated with the fuze setting mechanism, said elements being adapted to engage the nose and fuze ring respectively, a shaft having a helical groove, gearing differentially transmitting motion of said shaft to said movable elements, and a member sliding in the helical groove in said shaft adapted by the relative movement of the fuze setting mechanism lengthwise of the shaft to effect setting of the fuze.

7. In a gun assembly, a barrel having a breech, an elongated tray supported adjacent said breech for receiving a round of ammunition having a nose fuze adapted to be preset by rotation of the nose with respect to the fuze ring, fuze setting mechanism mounted for forward and rearward reciprocating movement along said tray and during its rearward movement being engageable with the nose of the ammunition, means for moving the fuze setting mechanism forwardly and rearwardly of said tray and adapted during rearward movement of said fuze setting mechanism to carry the ammunition to a rearward position for loading into the gun breech, relatively movable elements associated with the fuze setting mechanism, said elements being adapted to engage the nose and fuze ring respectively, a shaft having a helical groove, gearing differentially transmitting motion of said shaft to said movable elements, a member sliding in the helical groove in said shaft adapted by the relative movement of the fuze setting mechanism lengthwise of the shaft to effect setting of the fuze, and an indicator regulator adapted to rotate said shaft to vary the fuze setting.

8. In a gun assembly, a barrel having a breech, an elongated tray supported adjacent said breech for receiving a round of ammunition having a nose fuze adapted to be preset by rotation of the nose with respect to the fuze ring, fuze setting mechanism mounted for forward and rearward reciprocating movement along said tray and during its rearward movement being engageable with the nose of the ammunition, means for moving the fuze setting mechanism forwardly and rearwardly of said tray and adapted during rearward movement of said fuze setting mechanism to carry the ammunition to a rearward position for loading into the gun breech, relatively movable elements associated with the fuze setting mechanism, said elements being adapted to engage the nose and fuze ring respectively, a shaft, gearing differentially transmitting motion of said shaft to said movable elements, said shaft having a groove therein consisting of a helical portion and a straight portion, and a member sliding in said helical portion of the groove and being adapted by the relative movement of the fuze setting mechanism lengthwise thereof to effect setting of the fuze, said member sliding in said straight portion after the fuze setting mechanism leaves the helical

portion of the groove to effect further setting of the fuze upon rotation of said shaft.

9. In a gun assembly wherein a tray is mounted adjacent the gun breech for receiving a round of ammunition having a nose fuze adapted to be set by rotation of the nose with respect to the fuze ring the combination of; a support, a fuze setting mechanism mounted on said support and engageable with the nose of the ammunition and movable following the reception of the round of ammunition to shift the ammunition on said tray, said fuze setting mechanism comprising relatively rotatable nose engaging elements adapted to engage slots in the nose and the fuze ring during said shifting movement, and means linking the fuze setting mechanism to the support whereby the fuze setting operation occurs simultaneously with the movement of the ammunition into its shifted position.

10. In a gun assembly wherein a tray is mounted adjacent the gun breech for receiving a round of ammunition having a nose fuze adapted to be set by rotation of the nose with respect to the fuze ring the combination of; a support, a fuze setting mechanism mounted on said support and engageable with the nose of the ammunition and movable following the reception of the round of ammunition to shift the ammunition on said tray, said fuze setting mechanism comprising relatively rotatable nose engaging elements adapted to engage slots in the nose and the fuze ring during said shifting movement, and means linking the fuze setting mechanism to the support whereby the fuze setting operation occurs simultaneously with the movement of the ammunition into its shifted position, said linkage rotating the relatively movable elements in synchronism with the movement of the fuze setting mechanism.

11. In a gun assembly wherein a tray is mounted adjacent the gun breech for receiving a round of ammunition having a nose fuze adapted to be set by rotation of the nose with respect to the fuze ring the combination of; a support, a fuze setting mechanism mounted on said support and engageable with the nose of the ammunition and movable following the reception of the round of ammunition to shift the ammunition on said tray, said fuze setting mechanism comprising relatively rotatable nose engaging elements adapted to engage slots in the nose and the fuze ring during said shifting movement, and means linking the fuze setting mechanism to the support, whereby the fuze setting operation occurs simultaneously with the movement of the ammunition into its shifted position, said linkage rotating the relatively movable elements in synchronism with the movement of the fuze setting mechanism, and said linkage being adjustable during movement of the fuze setting mechanism to vary the ultimate setting of the fuze.

12. The combination with a gun assembly including an elongate tray mounted adjacent the gun breech arranged to receive at one end thereof a round of ammunition having a nose fuze settable by rotation of the nose relative to a fuze ring; of a support mounted for reciprocatory movement longitudinally of the tray, a fuze setting mechanism mounted on said support for reciprocation therewith and engageable with the nose of the ammunition upon reciprocation of said support to shift the ammunition toward the other end of said tray, said fuze setting mechanism comprising relatively rotatable nose and

13

fuze ring engaging elements, motion transmitting means differentially connected to said rotatable elements, means actuating said motion transmitting means responsive to relative movement of said fuze-setting mechanism and said tray, and means independently actuating said motion transmitting means responsive to fuze-setting adjustment.
